Inventor.

Kerry Wachenheimer,
By Wilmuth H. Thurston,

Attorney:

UNITED STATES PATENT OFFICE.

HARRY WACHENHEIMER, OF PROVIDENCE, RHODE ISLAND, ASSIGNOR TO WACHENHEIMER BROS., A FIRM COMPOSED OF JACOB WACHENHEIMER AND SAMUEL WACHENHEIMER, BOTH OF NEW YORK, N. Y., AND HARRY WACHENHEIMER, OF PROVIDENCE, RHODE ISLAND.

BAR-PIN.

1,356,027.

Specification of Letters Patent.

Patented Oct. 19, 1920.

Application filed May 24, 1916. Serial No. 99,690.

To all whom it may concern:

Be it known that I, HARRY WACHENHEIMER, of Providence, county of Providence, and State of Rhode Island, have invented certain new and useful Improvements in Bar-Pins; and I do hereby declare the following specification, taken in connection with the accompanying drawings, forming a part of the same, to be a full, clear, and exact description thereof.

The invention relates to bar-pins and the method of making the same, and has for its principal object the production of a pin of this character in which the body-portion of the pin is made from a single piece of metal, which greatly reduces the cost of manufacture. Another object of the invention is to provide the pin with a solid gem-support and perforated side-members formed integrally with the body of the pin.

To these ends the invention consists of the novel construction and arrangement of parts hereinafter described and more particularly set forth in the claims.

In describing the invention in detail reference will be made to the accompanying drawing, in which

Figure 1 is a bottom plan view of one of the blanks from which the body of the pin is formed;

Fig. 2 is an end view thereof;

Fig. 3 is a bottom plan view of the blank showing the second step in the construction of the pin;

Fig. 4 is an end view thereof;

Fig. 5 is a bottom plan view of the body-portion after the side-members have been bent up into position;

Fig. 6 is an end view of the same;

Fig. 7 is a top plan view of a completed pin;

Fig. 8 is a side view of the same;

Fig. 9 is a bottom plan view of the same;

Fig. 10 is an end view of the same;

Fig. 11 is a transverse sectional view on line $x-x$ of Fig. 8;

Fig. 12 is a top plan view of a modified construction where the front of the pin is left plain.

Referring to the drawing, the blank 1 is formed by rolling a piece of wire-stock so as to form a central longitudinal V-shaped rib-portion 2 and a lateral flange 3 extending from each side of the V-shaped rib 2 at

the base thereof. Formed upon the under surface of the body-portion at the point where each of the flange-members 3 joins the V-shaped rib 2 is a longitudinally extending groove 4.

After the wire has been rolled into this form it is cut into any desired lengths to form the blanks 1, as shown in Fig. 1. After this blank has been formed it is operated upon by a press to stamp out portions of the flange-members 3 to produce the openings 5 as shown in Fig. 3.

The next step consists in turning up the flange-members 3 at right angles to the face of the body-portion as shown in Fig. 5. An end-bar 6 is secured upon the cut-away end 70 of the V-shaped rib 2 and is of a suitable thickness to be flush with the free ends of the side-members, as shown in Fig. 10, and a suitable hinge-member 7 and catch-member 8 are secured upon the V-shaped rib 2. 75 Formed in the front face of the body-member is a series of conical cavities 9 in which suitable gems or ornaments 10 may be secured.

With the above construction it will be seen that the longitudinal grooves 4 permit the flange-members 3 to be easily bent up to form the side-members on the completed pin, and the V-shaped rib 2 not only strengthens the body-portion of the pin, but also forms 85 a suitable mounting for the stones, which is formed integral with the body-portion of the pin.

It will be understood that when a gem or ornament is not desired, the cavities 9 90 may be omitted and the front face of the body-portion may be left plain, as shown in Fig. 12 or ornamented in any desired manner.

What I claim as my invention and desire to secure by Letters Patent is:

1. A gem setting comprising a body-portion having an integral V-shaped rib formed upon the back thereof, two side-members formed integral with said body-portion, a series of openings in said side-members, a hinge- and catch-member mounted upon said V-shaped rib and a pin-tongue pivoted in said hinge-member.

2. A gem setting comprising a body-portion having an integral V-shaped rib formed upon the back thereof, two perforated side-members bent up at right angles to the face

of said body-portion, a hinge- and catch-member secured upon said V-shaped rib and a pin-tongue pivoted in said hinge-member.

3. An article of the character described comprising a body-portion having an integral V-shaped rib formed upon the back thereof, a series of cavities in the face of said rib, two perforated side-members bent up at right angles to the face of said body-

portion, two end-bars secured upon said V-shaped rib and flush with the free ends of said side-members, a hinge- and catch-member, and a pin-tongue pivoted in said hinge-member. 10

HARRY WACHENHEIMER.
